BOSTON CHAMPIONSHIP RECORD
ENDING IN OCTOBER 1879

Boston Type Foundry, No. 104 Milk Street, Boston.

UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,289, dated May 31, 1881.

Application filed February 8, 1881. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification, reference being had to the accompanying impression taken from said font.

My design consists of a font of capital letters, figures, and points, as shown.

The general character of the style is what may be called a "light-faced Gothic;" but it

has slightly-developed serifs which do not belong to the usual Gothic letter. It has also 15 a slope from right to left in the internal lines of A, B, E, F, H, P, and R, those lines being ordinarily horizontal. It further has certain peculiar curved lines in C G K S V W X Y.

I claim—

The design for a font of printing-types, as shown and described.

JOHN K. ROGERS.

Witnesses:

D. W. ROGERS,

D. W. ROGERS, Jr.
